[57] CLAIM

The ornamental design for a telephone display set base, substantially as shown and described.

DESCRIPTION

FIG. 1 is a perspective view of a telephone display set base showing my new design, the keypad being hidden; FIG. 2 is a perspective view thereof with the keypad exposed;

FIGS. 3, 5, 7 and 10 are respectively side, front and rear elevational views of the telephone display set base with the keypad hidden;

FIGS. 4, 6, 8 and 9 are respectively side, front and rear elevational views of the telephone display set base with the keypad hidden;

FIGS. 11 and 13 are respectively top and bottom plan views of the telephone display set base with the keypad hidden;

FIGS. 12 and 14 are respectively top and bottom plan views of the telephone display set base with the keypad exposed.
